* cited by examiner

Primary Examiner — Elizabeth Albert*(74) Attorney, Agent, or Firm* — David A. Gottardo(57) **CLAIM**

The ornamental design for a writing utensil grip, as shown and described.

DESCRIPTION

FIG. 1 is a perspective view of a writing utensil grip illustrating my new design;

FIG. 2 is another perspective view of a writing utensil grip of FIG. 1;

FIG. 3 is a plan view of the top of the writing utensil grip of FIG. 1;

FIG. 4 is a plan view of the bottom of the writing utensil grip of FIG. 1;

FIG. 5 is an elevation view of the right side of the writing utensil grip of FIG. 1;

FIG. 6 is an elevation view of the left side of the writing utensil grip of FIG. 1;

FIG. 7 is an elevation view of the forward end of the writing utensil grip of FIG. 1; and,

FIG. 8 is an elevation view of the rearward end of the writing utensil grip of FIG. 1.

The broken lines showing a pencil in FIG. 1 are included for the purpose of showing an environmental feature that forms no part of the claimed design.
